United States Patent Office.

WILLIAM A. BURY, OF GROSSE ISLE, MICHIGAN.

Letters Patent No. 100,011, dated February 22, 1870; antedated February 17, 1870.

IMPROVED RECLINING CHAIR.

The Schedule referred to in these Letters Patent and making part of the same.

To all whom it may concern:

Be it known that I, WILLIAM A. BURY, of Grosse Isle, in the county of Wayne, in the State of Michigan, have invented new and useful Improvements in Reclining-Back Chairs; and I do hereby declare that the following is a full and exact description thereof, reference being had to the accompanying drawings, (of which Figure 1 is a side view closed, Figure 2 is a square-notched catch, and Figure 3 is a side view reclining,) and to the letters of reference marked thereon.

The nature of my invention consists in constructing a chair with reclining back from A to C, hung to the chair at B; also a leg-rest from D to E, hung to the chair at D and connecting the back and leg-rest by means of rods or strips from C to G, also hung at C and E, (on which is fixed a foot-board, H,) which as the back reclines keep a horizontal (or nearly so) po-

sition, and by means of ratchet F or square-notched catch, fig. 2, which fall over front round of chair, securing any desired position of back in a stationary manner.

I am aware that chairs have been made with reclining backs, movable leg-rests and foot-boards, and these I do not claim as my invention; but

What I claim as my improvement in reclining-back chairs is—

The arrangement of the ratchet and its connection with the foot-rest and reclining back, in combination with the chair, as shown and for the purposes described.

WILLIAM A. BURY.
